SAFETY FUEL LINE

Max Dach, Flushing, N. Y.

Application May 7, 1941, Serial No. 392,314

7 Claims. (Cl. 210—165)

This invention relates to safety fuel lines, and more particularly to filters adapted to remove and separate water and other foreign matter from fuel, such as gasoline, in a fuel system. Due to atmospheric conditions and condensation, fuel tanks, whether on vehicles or in the nature of storage tanks, acquire a certain amount of moisture and foreign matter. This is particularly true where tanks must be cleaned and steamed for repair purposes or where the tanks are subject to substantial temperature changes.

While my invention is adapted for use in association with any form of tank, including a storage tank, it is particularly adapted for use in vehicles, such as passenger cars, busses, trucks, army vehicles, etc.

The present known types of separators are little more than enlarged fuel lines which fill with water and result in the water being drawn into the fuel lines and into the carburetor of engines. Moreover, they are subject to freezing and clogging.

An object of this invention is, therefore, to provide a separator to remove dirt and water from the fuel, and to provide means for draining such water or fuel without interfering with the operation of the fuel system.

A further object is to provide a separator in which surplus water and dirt will be returned to the tank or drawn off as desired.

A further object is to provide a mechanism which may be adapted to improve conventional separators without installing an entirely new device.

A further object of this invention is to provide an auxiliary line which will insure the passage of fuel through the line in the event the normal supply line is clogged.

In the accompanying drawing—

Fig. 1 is a cross-sectional view of my device shown in association with a fuel tank;

Fig. 2 is a slight modification of the device shown in Fig. 1;

Fig. 3 is a modification of my invention adapted to be used with a conventional separator;

Fig. 4 is another modified form thereof; and Fig. 5 shows an additional modification.

In Fig. 1 the separator 10 is situated between the tank 11 and the pump (not shown). The separator 10 consists of an upper housing 12 and a lower housing 13, which may be screwed into the upper housing at 14. A pipe or conduit means 15 runs from the separator to the fuel pump and a pipe or conduit means 16 leads

from the tank 11 to allow fuel to be drawn from the tank through the separator to the pump by suction.

Positioned in the separator is a cup 17 having edges 18 mounted on the edges of the lower casing 13. The cup 17 carries a strainer 19 positioned by the spring 20 engaging the cup 17 and positioning it. An opening 21 in the bottom of the cup 17 leads to the lower casing 13. The lower casing 13 is provided with a petcock 22 and a return pipe or conduit means 23 leads from the upper central portion to the tank 11.

In operation, fuel, such as gasoline, is drawn from the tank 11 through the pipe 16 into the chamber 24 formed by the strainer 19 in the cup 17. Any heavier matter, such as water or foreign matter, will fall by gravity to the bottom of the chamber 24 and pass through the opening 21 into the lower housing 13 where it may be drawn off through the petcock 22, or, should it rise to the level of the return pipe 23, returned to the tank 11. It will be readily appreciated that not only does the pipe 23 act as a return line but it may also be used as an auxiliary fuel line and, in the event that the pipe 16 is clogged, the suction from the pump may draw fuel from the tank through the pipe 23.

In the modified form shown in Fig. 2, the return pipe 25 runs from the petcock 22 to the bottom of the tank 11. This modified form operates in the same manner as the form shown in Fig. 1, but would be more adaptable to installations where, due to the use of the vehicle, the position of the separator is not stable. This would be particularly true in airplanes which are often banked or turned sharply and in which any accumulated amount of water might be thrown back into the line.

In the modified form shown in Fig. 4, the upper casing 30 is adapted to receive the conventional glass cup 31 held in place by the conventional swinging bracket 32. The supply pipe 33 has a tube 34 extending into the strainer 35. A return pipe 36 is tapped into the bottom of the housing 30 to return water or foreign matter which may rise to the level of the pipe 36, thus preventing it from being drawn through the pipe 37 to the pump. Since, in the event of freezing or excessive flow of fuel, the bottom 38 of the tube 34 might be covered and the suction destroyed, a vent 39 is provided with a tube 34 to insure the free flow from the tank to the pump.

The form shown in Fig. 3 operates in the same manner as that shown in Fig. 4, except that a metal cup 40 is substituted for the conventional

glass cup 31. A return pipe 41 may then be tapped into the cup device adjacent the lower portion thereof, and a petcock 42 may be provided for drainage.

In the form shown in Fig. 5, the casing 50 is adapted to receive a conventional glass cup 51 and is provided with a pipe 52 tapped into the top 53 of the casing. A strainer member 54 is provided adjacent the top of the casing, and the feed line 55 enters the casing at 56 below the strainer. A return pipe 57 is provided in the lower portion of the casing. In this form the reversal of the pump and fuel lines avoids the possibility of a lock in the suction line and eliminates the necessity of the vent.

It will be appreciated that while my other modifications show slightly different structure, the basic principle of my invention is the same in any form in which there is furnished a suitable chamber of sufficient depth to allow the separation of the water or foreign matter from the fuel and the return of said foreign matter to the tank, or the drainage thereof from the separator, thus avoiding the possibility of the foreign matter being drawn into the pump and carburetor and thus avoiding the possibility of large amounts of water or foreign matter collecting in the separator and freezing.

It will also be appreciated that with my improved fuel line an auxiliary line is provided, and that, should the top line be clogged, fuel will be drawn by the pump through the auxiliary line, thus insuring a continued flow. If large amounts of water accumulate in the chamber, the auxiliary line will of course be covered and the water, being heavier, will normally settle to the bottom of the chamber so that gas may be drawn through the auxiliary line if necessary.

I claim:

1. In a fuel system having a supply tank and a pump, a separator, conduit means connecting the tank and the separator and connecting the separator and the pump and providing fluid flow communication between the tank, the separator and the pump, a strainer within said separator and disposed between the tank and pump conduit connections therewith, a chamber below said strainer to collect water and foreign matter, and return conduit means connecting said chamber and said tank, the connection between said return conduit and said chamber being on a level with, or above the bottom of said tank.

2. In a fuel system having a supply tank and a pump adapted to draw fuel therefrom by suction, a separator situated between the tank and the pump, means providing fluid flow communication between said tank and separator, and between said separator and pump, a strainer in said separator disposed across the path of fluid flow therethrough, a chamber beneath said strainer element to collect water and foreign matter carried by the fuel, and a return pipe connecting said chamber with said tank, the connection between said return pipe and said chamber being on a level with or above the bottom of said tank.

3. In combination with a fuel system including a tank and a pump, a separator situated between said tank and pump, said separator comprising an upper housing, a straining member in said upper housing, a pipe leading from said tank

into the upper housing at one side of said straining member, a pipe leading from said upper housing at the opposite side of said straining member to said pump, a lower housing comprising a settling chamber for water and foreign matter, and a return pipe leading from said separator at a point below said straining member to said tank, the point of connection between said return pipe and said separator being on a level with or above the bottom of said tank.

4. In combination with a fuel system including a tank and a pump, a separator situated between said tank and pump, said separator comprising an upper housing containing a straining member and a lower housing forming a settling chamber below said straining member, means for retaining said housing members together in fluid tight relation, a petcock on said lower chamber and a return pipe leading from said lower chamber to said tank, the point of connection between said return pipe and said lower housing being on a level with or above the bottom of said tank.

5. In combination with a fuel system having a pump and a fuel tank, a separator situated therebetween, said separator comprising a housing member having a settling chamber secured to the lower end thereof, a pipe leading from the top of the housing member to said pump, a strainer situated in said housing member, a pipe leading from the fuel tank to said housing member and connected thereto at a point below said strainer and a return pipe leading from the lower portion of said separator to said tank, the point of connection between said return pipe and said separator being on a level with, or above the bottom of said tank.

6. In a fuel system having a supply tank and a pump adapted to draw fuel therefrom by suction, a fuel receiving member situated between said tank and pump, conduit means for establishing fluid flow communication between the tank and fuel receiving member and between said fuel receiving member and said pump, a settling chamber in said fuel receiving member for collecting water and foreign matter, and a return pipe running from said settling chamber to said tank, the point of connection between said return pipe and said settling chamber being on a level with or above the bottom of said tank.

7. In combination with a fuel system including a tank and a pump, a separator situated between the tank and pump, said separator including a settling chamber, an upper housing engaging the outside of the top of said settling chamber, a cup member positioned on the top edge of said settling chamber and having an aperture therethrough, a straining member positioned in said cup, a spring engaging said cup and said upper housing to position said cup and said straining member, an inlet pipe from said tank communicating with the upper housing and discharging within said straining member, an outlet pipe in said upper housing outside of said straining member and a return pipe connected between the tank and said settling chamber, the point of connection between said return pipe and said settling chamber being on a level with, or above the bottom of the tank.

MAX DACH.
